UNITED STATES PATENT OFFICE

ALEXANDER J. BALTSOIS, OF BROOKLYN, NEW YORK

ALARM DEVICE FOR CLOCKS

Application filed March 2, 1931. Serial No. 519,548.

This invention relates to improvements in clocks, and has especial reference to alarm devices for clocks and indicating means therefor.

The invention contemplates the provision of means in conjunction with parts of a clock, to the end, that an alarm will be given regularly and continue to sound for a predetermined interval of time; that the alarm after being started may be stopped at will to shorten the interval of sounding; that an indicator or On sign will be brought into registry with a sight opening in the dial of the clock while winding the spring of the device; that an indicator or Off sign will be brought into registry with said sight opening with the stopping of the alarm; that the alarm will sound during the time it requires to change from the On sign to the Off sign; and that an indicator or Silent sign may be brought into registry with said sight opening and at the same time render the alarm device inactive.

A further object of the invention is the provision in a clock of a spring actuated means which is common to the time movement and the alarm movement.

With the foregoing and other objects in view, the invention resides in the combinations, constructions and operations of the parts hereinafter fully described and illustrated in the accompanying drawings, in which:

Figure 1 is a front view of a clock works, embodying certain features of the invention, the parts being shown in the On relationship;

Fig. 2 is a fragmentary front view showing certain parts in the Off relationship;

Fig. 3 is a section on the line 3—3 of Fig. 4;

Fig. 4 is a section on the line 4—4 of Fig. 3;

Fig. 5 is a face view of a portion of the clock dial;

Fig. 6 is a section through the spring and connected parts;

Fig. 7 is a detail section;

Fig. 8 is a view of the alarm train and verge;

Fig. 9 is a view of the indicator train.

The present invention involves a clock

inafter fully described. The clock works have combined therewith an alarm mechanism or movement. The time movement or mechanism and the alarm movement or mechanism are operated by a spring which is common to both the time movement and the alarm movement. In the drawings the watch works are indicated generally at 10 and include the front and rear plates 11 and 12 held in spaced relation. The dial of the clock is arranged in front of the plate 11, and a portion of the said dial is shown in Fig. 5 and designated 13. The dial 13 has a sight opening 14 therein for a purpose to be hereinafter explained. In accordance with one of the main features of the invention there is provided a spiral spring 15 which has one end thereof secured as at 16 to an arbor 17 and its opposite end secured as at 18 to a drum 19. The arbor 17 is supported for rotation by suitable bearings, respectively, on the plates 11 and 12. The drum 19 is mounted for rotation on the arbor 17. The drum has a toothed wheel 20 which operates the time movement. A ratchet wheel 21 is fixedly secured to the arbor 17 by a screw 22 which extends through a hub 23 integral with the wheel 21. A toothed wheel 24 is mounted for rotation on the hub 23 and is held in place by a collar 25 secured in place on the hub 23 by the screw 22. The wheel 24 carries a spring actuated pawl 26 which coacts with the teeth of the ratchet wheel 21 in winding the spring 15. The arbor 17 has secured thereto a winding key 27. The spring 15 is wound by manipulating or turning the key 27 in a clockwise direction looking toward the spring from the rear. The spring 15 when wound causes the drum 19 and its wheel 20 to rotate in a clockwise direction and the wheel 24 to rotate in a counterclockwise direction looking toward the spring 15 from the rear. It is to be understood that the wheel 20 in operating the time movement will be resisted to the extent required for operating the same, and that the wheel 24 will rotate only when the alarm movement is released.

On reference to Fig. 8 it will be apparent that the wheel 24 operates the alarm train 28

and that this alarm train operates the striker or verge 29. The verge 29 has connected therewith members 31, 32 and 33 for purposes to be explained.

- 5 It is to be understood that the alarm mechanism will include the usual setting and release means including a flexible member 34 carried by the plate 11 which cooperates with the member 33 of the verge. The member 34, 10 when released by the wheel 35 at a predetermined time, disengages itself from the member 33 and thereby allowing the alarm mechanism to operate.

15 In accordance with another important feature of the invention there is provided an indicator 36 which is mounted for rocking movement on an arbor 37 supported for rocking movement by the plates 11 and 12. The indicator 36 consists of a radial arm 38 having an enlarged end 39 which surrounds the arbor 37 and disks 40 and 41 on the opposite end of the arm. The disks 40 and 41 have distinguishing indicia or markings thereon, 20 in the present instance, consisting of the word On on the disk 40, and the word Off on the disk 41. The disks 40 and 41 are positioned so as to be moved into and out of registry with the opening 14 in the dial 13. Means is provided for manually operating the indicator 36 to bring the disks 40 and 41 into and out of registry with the opening 14 and also to stop and release the verge 29. The said means includes a disk member 42 which is fixedly mounted on the arbor 37. A bowed 25 spring 43 surrounds the arbor 37 between the end 39 of the indicator 36 and the member 42 to set up frictional engagement of the member 42 with the indicator 36. The provision of the spring 43 will cause the indicator 36 to move with the disk member 42 but will also allow the disk member 42 to move with respect to the indicator 36. The indicator 36 is limited in its movement in opposite directions with respect to the disk member 42 by pins 44 and 45 carried by the disk member 42, which pins are encountered by the arm 38. The indicator 36 is also limited in its movement in relation to the dial 13 in order to insure the registration of the disks 40 and 41 with the opening 14 in the dial. This is accomplished by an arm or stop 46 integral with the end 39 of the indicator arm 38 and stop pins 47 and 48 on the plate 11. A spring 49 has one end thereof 30 connected with the disk member 42 and its opposite end bears on a pin 50 carried by the arm 46. The spring constantly acts to yieldably retain the arm 38 of the indicator in engagement with the pin 44. The disk member 42 has a toothed sector 51 secured to or formed integral therewith. The sector 51 co-operates with an indicator train 52 which is operated by a pinion 53 rotatable with the arbor 17. The train 52 includes a 35 pinion 54 which is under the influence of a

spider spring 55. The pinion 54 is positioned for meshing engagement with the toothed sector 51. By reason of the use of the spring 55, the pinion 54 will be caused to rotate with the train 52 to operate the sector 51, and also to allow the pinion 54 to rotate freely without influencing the train 52 when the disk member 42 is operated to move the indicator 36.

40 It will now be understood that when the key 27 is manipulated to wind the spring 15, this will cause the train 52 to operate through the intervention of the arbor 17 and pinion 53, and, as a consequence, the pinion 54 will impart movement to the sector 51 and disk member 42. The indicator 36 will therefore move with the disk member 42 by reason of the spring 43 thereby bringing the disk 40 in registry with the opening 14. The On sign will therefore appear in the opening, indicating that the alarm is on. The indicator 36 is limited to this position by the arm 46 encountering the pin 48. When the member 34 is released so as to disengage itself from the member 33, the verge 29 will be released for operation by the spring 15 through the intervention of the train 28. This will cause the alarm to be sounded for a predetermined period. It will also be apparent that the train 52 will operate causing the On disk to be moved out of registry with the opening 14, and the Off disk 41 to be moved into registry with the opening 14. This is accomplished through the intervention of the sector 51, disk member 42, spring 43 and the arm 38 of the indicator 36. The indicator 36 is limited to movement to its off position by the arm 46 encountering the stop 47. At this time a pin 56 carried by the arbor 37 engages the member 31 of the verge 29 thereby stopping the operation of the alarm mechanism.

45 It will be understood that the arbor 37 may be rotated manually by a handle 57 exteriorly of the clock case to move the indicator 36 into and out of its on and off positions. It will therefore be understood that the handle 57 may be manipulated to stop the alarm mechanism after it has been started automatically so as to shorten the period of operation of the alarm. The spring 49 insures the meshing engagement of the sector 51 with the pinion 54 when the indicator is in the On position. If desired, an additional spring 58 may be employed to help the spring 49.

50 If desired, and as shown in the present instance, the alarm mechanism may be rendered inactive by additional means which also indicates that the alarm mechanism has been rendered inactive. The said means includes an arm 59 connected at one end with a pivot 60 supported by the plates 11 and 12, and its opposite end having a disk 61 having the word Silent thereon. The pivot 60 has con- 55

nected therewith a manipulator 62 which extends exteriorly of the case of the clock. The pivot 60 also has connected therewith a member 63 which is engageable with the member 32 of the verge 29 to render the alarm mechanism inactive. It will now be understood that when the member 63 is swung by manipulating the handle 62, the disk 61 will be brought into registry with the opening 14 in the dial 13. The member 63 may be disengaged at will. The alarm mechanism will operate in accordance with the other features of the invention as set forth above.

I claim:

1. The combination with a clock alarm device, of an indicator member mounted for movement into and out of indicating position, means operable by said device to move said indicator member into and out of the indicating position, and means connected with said indicator member operable to move said indicator member into its indicating position and to render the alarm device inactive while the indicator member is in its indicating position.

2. The combination with a clock alarm device including a vibrating clapper or the like; of an indicator member mounted for movement into and out of an indicating position, means operable by said device to move said indicator member into and out of the indicating position, additional means connected with said indicator member manually operable to move said indicator member into and out of its indicating position, and means forming a part of the last named means engageable with said clapper to render said alarm device inactive while said indicator member is in its indicating position.

3. An indicator for a clock alarm device including the combination of a rotatable member, an indicator member, means having frictional engagement with said indicator member to move said indicator member into different positions, means in frictional engagement with said rotatable member, and means connected with said first means which coacts with the second means to move said indicator member into different positions in response to the rotation of said rotatable member.

4. An indicator for a clock alarm device including the combination of a rotatable member, an indicator member, a pinion in frictional contact with said rotatable member to rotate therewith and to rotate relative thereto by overcoming the frictional contact, and a toothed sector in frictional engagement with said indicator member which coacts with said pinion to move said indicator member into different positions in re-

sponse to the rotation of said rotatable member.

5. The combination with an alarm clock having a dial having a sight opening therein; of an indicator member mounted for movement into and out of registry with said opening, means operable by the alarm mechanism of the clock to move said indicator member into and out of registry with said opening, and manually operable means adapted to move said indicator member into and out of registry with said opening independent of said alarm mechanism operated means, and said manually operable means having provision for controlling the operation of said alarm mechanism.

6. In combination with the alarm mechanism of a clock, an indicator mounted for rocking movement, fixed stops, means on said indicator engageable with said stops to limit the movement of the indicator, operating means having frictional engagement with said indicator to cause the rocking movement thereof but allowing movement of said indicator in relation to said operating means, resilient means acting on the indicator and operating means having a normal tendency to urge said indicator to move in one direction in relation to said operating means.

7. In combination in an alarm clock, an indicator for the alarm mounted for rocking movement, fixed stops, means on said indicator engageable with said stops to limit the movement of the indicator, operating means having frictional engagement with said indicator to cause the rocking movement thereof but allowing movement of said indicator in relation to said operating means resilient means acting on the indicator and operating means having a normal tendency to urge said indicator to move in one direction in relation to said operating means.

8. In combination in an alarm clock, an indicator for the alarm mounted for rocking movement, fixed stops, means on said indicator engageable with said stops to limit the movement of the indicator, operating means having frictional engagement with said indicator to cause the rocking movement thereof but allowing movement of said indicator in relation to said operating means, resilient means acting on the indicator and operating means having a normal tendency to urge said indicator to move in one direction in relation to said operating means, and a toothed sector connected with said operating means to cooperate with said alarm.

ALEXANDER J. BALTSOIS.
